UNITED STATES PATENT OFFICE.

JOHN F. O'CONNOR, OF CHICAGO, ILLINOIS, ASSIGNOR TO WILLIAM H. MINER, OF CHAZY, NEW YORK.

REFRIGERATOR-DOOR CLOSING AND LOCKING MEANS.

1,152,042.

Specification of Letters Patent. Patented Aug. 31, 1915.

Application filed August 17, 1914. Serial No. 857,107.

To all whom it may concern:

Be it known that I, JOHN F. O'CONNOR, a citizen of the United States, residing at Chicago, in the county of Cook and State of Illinois, have invented a certain new and useful Improvement in Refrigerator-Door Closing and Locking Means, of which the following is a full, clear, concise, and exact description, reference being had to the accompanying drawings, forming a part of this specification.

This invention relates to improvements in refrigerator door closing and locking means, and more particularly to closing and locking means for doors of refrigerator cars, although the device is also equally useful in connection with any doors of a car or other construction such, for instance, as the end doors of an automobile car.

An object of the invention is, to provide a closing and locking mechanism which will firmly move the doors to closed position, and securely hold them locked in such condition.

The invention furthermore consists in the parts and devices, and in the novel combinations of the parts and devices herein shown and described or claimed.

In the drawings forming a part of this specification, Figure 1 is a side elevation of a refrigerator car door showing my improvements in connection therewith; Fig. 2 is a horizontal sectional view taken substantially on the line 2—2 of Fig. 1; Fig. 3 is an enlarged detail horizontal sectional view showing more particularly the meeting edges of the doors, the nut and bolt for operating the locking lever, and the method of mounting the nut in the doors; Fig. 4 is a view similar to Fig. 2, showing another form of my invention; Fig. 5 is an enlarged detail sectional view taken substantially on the line 5—5 of Fig. 4; and Fig. 6 is a detail elevational view showing more particularly the means for detachably connecting the free end of the locking lever with one of the doors.

Referring now more particularly to Figs. 1 to 3 inclusive, 10 and 11 denote the doors, which are mounted on hinges 12—12 and arranged to swing outwardly in opposite directions, the door 10 having its free edge beveled as indicated at 13, and the free edge of the door 11 being oppositely beveled, each of the free edges being covered with

a suitable packing 14 of canvas or the like, and one of said doors being provided with a spring pressed backing strip 15, the backing strip 15 being mounted in the door 11, as shown in the drawings. Between the door jambs 16—16 and the adjacent edges of the swinging doors, similar insulating packings 17 are provided,—see Fig. 2. For closing the doors and holding the same locked, I provide a lever or arm 18, which is pivotally connected to the door 10 at 19, the free end of said lever 18 being rounded off as indicated at 20, and adapted to slidably engage a wear plate 21 on the inner side of the door 11. Pivotally connected to the lever 18 at about the center thereof by a pin 22 is a threaded bolt 23 which extends through the door 10, and is operated in the manner about to be described, said bolt having at the outer end thereof a limiting nut 123. The door 10 is provided with a recess 24 extending entirely therethrough, and located near the free edge thereof and opposite the lever 18. Mounted in said recess, and permanently attached to the door 10 is a hollowed bearing which comprises a cup-shaped member 25 secured in place as by screws 26, and a plate 27, also secured in place by suitable means such as screws 26, said plate 27 and cup-shaped member 25 having inter-engaging flanges 30,—see Fig. 3. The cup-shaped member 25, near the bottom thereof, is provided with a concave bearing surface 31. A convex bearing surface 32 is also provided in which is rockably mounted a nut 33, said nut being threaded to coöperate with the threaded bolt 23, as will be understood. The nut 33 has an outwardly extended tubular member 34 which, at its inner end, is provided with a convex shoulder 35 coöperable with the concave surface 31, and forming therewith a tight smooth fit. At its outer end the tubular member 34 has formed, rigidly or integrally therewith, a hand-wheel 36 whereby the nut 33 may be easily rotated in either direction. At its inner end the nut 33 is interiorly threaded as indicated at 37, and secured thereto is a cap or washer 38, the washer or cap being held in place and prevented from accidental removal by means of a screw or other suitable fastening device 39. At one portion in its periphery, the hand-wheel 36 is provided with a recessed projection 40, over which is 110

adapted to fit a hasp 41 pivotally connected to the door by a staple 42. When the hasp is fitted over the projection 40, a sealing wire 43 may be inserted through the perforated member 40, and a seal 44 applied thereto in the usual manner, to thereby prevent tampering with the door after it has been securely locked. On the outer side of the door 11, a plate 45 is attached thereto which is rabbeted as at 46, and with which co-operates an extension 47 formed on the cup-shaped bearing member 25.

The operation of the device is as follows: In the drawings, the doors are shown as in closed position, and to open them, the hand-wheel 36 will be rotated counter-clockwise, which will turn the nut 33 and thereby force the bolt 23 and the lever 18 inwardly. As soon as the lever 18 has been pushed inwardly a sufficient distance, the hand-wheel 36 may be grasped, and the doors 10 and 11 pulled outwardly until they have been opened to such an extent that the free edge of the door 11 will readily pass by the extended flange 47, whereupon the door 11 may be thrown completely open, and afterward the door 10 can be similarly thrown completely back. During the rotation of the hand-wheel 36, it will be noted that the gradually changing angular relation between the bolt 23 and the lever arm 18 is accommodated on account of the convex bearing provided for the nut 33, and the nut 33 is prevented from movement transversely of the door 10 by means of the collar or washer 38 and the shoulder formed on the inner end of the tubular extension 34.

In closing the doors, the reverse operation of that above described takes place. As the hand-wheel 36 is rotated clockwise, the flange 47 will engage the plate 45 and force both doors inwardly, the free end of the lever 18 taking bearing on the plate 21, and sliding thereon as the operation continues. When the doors are fully closed, it is apparent that the same cannot come open accidentally, and, furthermore, that there is a substantially air-tight fit between the concave bearing 31 and convex shoulder 35, which is desirable in preventing air from circulating between the outside and the inside of the doors.

In the construction shown in Figs. 4, 5 and 6, the bolt, hand-wheel, nut, bearing therefor, and inter-engaging members on the free edges of the two hinged doors are the same, and hence a repetition of the description of these parts is omitted. The free end of the lever 118, however, is provided with a pivoted T-shaped slide 50 pivotally connected to the arm 118 as by a detachable pin 51. The lateral extensions 52-52 of the slide 50 slide in ways 53 formed in a plate 54 secured to the inner side of the door 11. The ways 53 are formed

by overhanging flanges 55 which, however, only extend approximately half the length of the plate 54, said flanges terminating at 56, as indicated in Figs. 4 and 6. Beyond the ends of the flanges 56 the recess in the plate 54 is widened sufficiently for the extensions 52 of the slide 50 to be easily removed therefrom, whereby the slide 50 may be disengaged from the door 11.

The operation of the construction shown in Figs. 4, 5 and 6 is quite similar to that hereinbefore described for the structures shown in Figs. 1 to 3 inclusive, except that in closing the doors, the same will be relatively positioned so that the slide 50 may be inserted in the enlarged opening in the plate 54, after which, as the doors are gradually forced home, the slide 50 engages in the ways 53 until the doors are securely locked. In opening the doors, rotation of the hand-wheel counter-clockwise tends to force the lever arm 118 backwardly, but on account of the same being connected at both ends to the doors 10 and 11, the continued counter-clockwise rotation of the hand-wheel will automatically serve to force the free edges of the two doors outwardly until such time as the slide 50 has reached a point where it may be disengaged from the plate 54.

While I have herein described specifically two forms of my invention, I am aware that the invention may be embodied in different constructions than those shown, and I do not wish to be limited by the drawings and description herein, except as defined in the claims appended hereto.

I claim:

1. In a door locking mechanism, the combination with a door directly hinged along one edge thereof, of a lever pivoted at one end to said door, said lever having its free end extended beyond the free edge of the door, and adapted to bear on the surface of an adjacent member, and adjustable tightening means connecting said lever to said door, said means being attached to the lever intermediate its ends.

2. In a door locking mechanism, the combination with a pair of oppositely swinging hinged doors, of a lever carried by one of said doors, and having its free end extended so as to bear on the other door, and adjustable means connecting said lever with one of the doors.

3. In a door locking mechanism, the combination with a pair of oppositely swinging hinged doors, of a member carried by one of said doors, said member extending over, and adapted to engage the other of said doors, and means adjustably connecting said member with the door by which it is carried.

4. In a door locking mechanism, the combination with a pair of oppositely swinging hinged doors, of a lever carried by one of said doors, and having its free end extended

so as to bear on the other door, and adjustable means connecting said lever with one of the doors, said means including a nut and a bolt coöperable therewith.

5. In a door locking mechanism, the combination with a pair of oppositely swinging hinged doors, of a lever carried by one of said doors, and having its free end extended so as to bear on the other door, and adjustable means connecting said lever with one of the doors, said means including a threaded bolt carried by said lever and extending through the door, and a nut rotatably mounted in the door.

15. 6. In a door locking mechanism, the combination with a pair of oppositely swinging hinged doors, of a lever carried by one of said doors and having its free end extended so as to bear on the other door, a nut rotatably mounted in the door by which said lever is carried, a bolt pivotally connected to the lever arm and extending through said nut, and means for rotating said nut.

25. 7. In a door locking mechanism, the combination with oppositely swinging hinged doors, one of said doors having a bearing mounted therein, of a nut rotatably mounted in said bearing, a lever arm pivotally connected to one of said doors, and a bolt pivotally connected to said lever arm and extending through said nut.

35. 8. In a door locking mechanism, the combination with a pair of oppositely swinging hinged doors having coöperating beveled edges, of means mounted on the doors for forcing said doors to closed position, and holding the same locked, said means including a pivotally mounted lever, a threaded bolt pivotally connected to the said lever, a nut coöperable with said bolt, and a bearing in which said nut is rotatably and rockably mounted.

45. 9. In a door locking mechanism, the combination with a pair of hinged doors, one of said doors having a projection at its free edge adapted to overlap and engage the free edge of the opposite door to thereby move the latter, of a lever pivotally connected to the door having said projection, and adjustable means connecting said lever and the door by which it is carried, whereby the angular relation between the lever and said door may be varied.

55. 10. In a door locking mechanism, the combination with a pair of oppositely swinging, pivoted doors, of a lever pivotally connected to one of said doors, means, including a rotatable nut, for adjusting the position of the said lever relative to the door by which it is carried, and a bearing for said nut, said

bearing comprising a hollow member secured to the door, said bearing and nut having coöperating curved surfaces to permit relative movement and to maintain a tight fit therebetween.

65

11. In a door locking mechanism, the combination with a pair of oppositely swinging, pivoted doors, of a lever pivotally connected to one of said doors, means, including a rotatable nut, for adjusting the position of the said lever relative to the door by which it is carried, and a bearing for said nut, said bearing comprising a hollow member secured to the door, said bearing and nut having coöperating curved surfaces to permit relative movement and to maintain a tight fit therebetween, said nut being provided with a hand-wheel for operating it.

75

12. In a door locking mechanism of the character described, the combination with a pair of oppositely swinging hinged doors, of a lever pivotally connected to one of said doors, means for adjusting the relative position of said lever to the door by which it is carried, and means for detachably connecting the free end of said lever with the other door.

80

13. In a door locking mechanism of the character described, the combination with a pair of oppositely swinging hinged doors, of a lever pivotally connected to one of said doors, means for adjusting the relative position of said lever and the door by which it is carried, and means for detachably connecting the free end of said lever with the other door, said last named means including a pivotally mounted slide carried by the lever, and a plate carried by the door, said slide and plate having inter-fitting, relatively slidable flanges.

90

14. In a door locking mechanism of the character described, the combination with a pair of oppositely swinging hinged doors, of a lever pivotally connected to one of said doors, means for adjusting the relative position of said lever to the door by which it is carried, and means for detachably connecting the free end of said lever with the other door, said means including a plate secured to the door, and a slide pivotally connected to the free end of the lever, said slide having a T-shaped head engageable with the plate, the plate having an enlarged recess at one portion thereof permitting the T-shaped head of the slide to disengage from the plate.
